CLAIM

The ornamental design for a multifunctional docking station for a cleaning robot, as shown and described.

DESCRIPTION

1.1 is a front view of a first embodiment of a multifunctional docking station for a cleaning robot;

1.2 is a back view thereof;

1.3 is a left view thereof;

1.4 is a right view thereof;

1.5 is a top view thereof;

1.6 is a bottom view thereof;

1.7 is a front top perspective views thereof;

1.8 is a back top perspective views thereof;

1.9 is a back bottom perspective views thereof.

2.1 is a front view of a second embodiment of a multifunctional docking station for a cleaning robot;

2.2 is a back view thereof;

2.3 is a left view thereof;

2.4 is a right view thereof;

2.5 is a top view thereof;

2.6 is a bottom view thereof;

2.7 is a front top perspective views thereof; and

2.8 is a back top perspective views thereof.

(Continued)

The broken lines in the reproductions depict portions of the multifunctional docking station for a cleaning robot that form no part of the claimed design.
